UNITED STATES PATENT OFFICE.

ABRAHAM MILLER, OF NEW YORK, N. Y.

DESIGN FOR A LIGHTING-FIXTURE ARM.

58,497.

Specification for Design.

Patented July 26, 1921.

Application filed December 28, 1920. Serial No. 433,653. Term of patent 3½ years.

To all whom it may concern:

Be it known that I, ABRAHAM MILLER, a citizen of the United States, and a resident of the city of New York, borough of the Bronx, county of Bronx, and State of New York, have invented a new, original, and ornamental Design for Lighting-Fixture Arms, of which the following is a specification.

Reference being had to the accompanying drawing, forming part thereof in which;

Figure 1 is a plan view of a lighting fixture arm.

Fig. 2 is a side view thereof.

I claim.

The ornamental design for a lighting fixture arm, substantially as shown.

ABRAHAM MILLER.
